UNITED STATES PATENT OFFICE.

MAX KOCH, OF RATINGEN, GERMANY.

ROLLING-MILL FOR METAL TUBES.

984,569.

Specification of Letters Patent. Patented Feb. 21, 1911.

Application filed March 31, 1910. Serial No. 552,517.

To all whom it may concern:

Be it known that I, MAX KOCH, a citizen of Germany, residing at Ratingen, Germany, have invented new and useful Improvements in Rolling-Mills for Metal Tubes, of which the following is a specification.

This invention relates to a rolling mill of novel construction, more particularly designed for rolling out metal tubes.

In the accompanying drawing: Figure 1 is an elevation partly in section of a rolling mill embodying my invention, and Fig. 2 a similar view showing the parts in a different position.

In the machine frame are journaled two sets of rolls a, a' and b, b' , placed at a distance from each other, and adapted to be rotated in opposite directions. The upper rolls a, b , are adapted to be reciprocated vertically by a hydraulic piston through double rack z , pinions r and spindles g , in such a manner that when one of the rolls rises, the other roll descends. With each roll pair coöperates a mandrel d, d' adapted to be reciprocated by friction rollers f, f' and to be locked in position by pin v , so that it will not be retracted during the rolling operation. Intermediate the machine frame and rollers f, f' there are arranged below mandrels d, d' a pair of troughs e, e' that serve to support the workpiece when the mandrels are withdrawn therefrom.

The tube to be rolled is adapted to be advanced by pushers t, t' depending from carriages i , which travel on transverse beams i' and which are reciprocated by an electro-motor or similar device j . Upon the inner ends of mandrels d, d' are adapted to be removably fitted a pair of bulged heads h, h' , which may be readily slipped on or off the mandrels.

With the position of parts indicated in Fig. 1 mandrel d' is retracted, roll b is raised, roll a is lowered, mandrel d with its head h being projected between rolls a, a' . The work piece is then placed into right hand trough e' and pusher t' is started to advance the work piece toward rolls a, a' ,

which will thus roll it over head h . Mandrel d' is then advanced and locked by a pin similar to the pin v shown on the left of Fig. 1, head h' is fitted on the mandrel, roll a is raised, and roll b is lowered. The pusher t will now advance the work piece toward rolls b, b' thereby stripping head h off mandrel d said head falling into the pit k below the machine frame. The work piece is thus rolled by rolls b, b' over head h' , which operations are repeated until the tube has acquired the thickness desired. If the finished tube is to be removed, lock pin v is withdrawn and the mandrel carrying the tube is retracted, during which manipulation the head h or h' is stripped off same.

It will be seen, that with my improved rolling mill the mandrels do not require any attendance, as they remain stationary during the reciprocative movement of the work piece. The manipulation is limited to fitting new heads or refitting the previously slipped off heads to the mandrels and to operating the top rolls and pushers. In this way the operation of the mill is greatly facilitated, while time and labor are economized.

I claim:

1. A rolling mill comprising two sets of respectively vertically aligned coöoperating rolls, means for rotating said roll sets in opposite directions, means for alternately lowering and raising the top rolls of said sets, a pair of axially aligned mandrels coöperating with the rolls, and heads loosely mounted upon the mandrels.

2. A rolling mill comprising two sets of respectively vertically aligned coöoperating rolls, means for rotating said roll sets in opposite directions, means for alternately lowering and raising the top rolls of said sets, a pair of axially aligned mandrels coöperating with the rolls, heads loosely mounted upon the mandrels, and means for axially displacing the mandrels.

MAX KOCH. [L. S.]
